INVENTOR

Joseph M. Fox
BY
H. C. Davis
ATTORNEY.

UNITED STATES PATENT OFFICE.

JOSEPH M. FOX, OF PEEKSKILL, NEW YORK.

COMBINED SCARF-TIP AND FASTENER.

SPECIFICATION forming part of Letters Patent No. 463,268, dated November 17, 1891.

Application filed October 28, 1890. Serial No. 369,633. (No model.)

To all whom it may concern:

Be it known that I, JOSEPH M. FOX, a citizen of the United States, residing at Peekskill, in the county of Westchester and State 5 of New York, have invented a new and useful Necktie Attachment, of which the following is a specification; and I declare it to be a full, clear, and exact description of the invention, which will enable others skilled in the 10 art to which it appertains to make and use the same.

My invention relates to fastenings for the style of tie which consists of a bow having a band to pass around the neck, the free end of 15 the band being secured by passing it through the tie and hooking on a pin fixed in the bow; and its object is to provide the said strap with a simple means for fastening the tie to the shirt-bosom to keep it from rising about 20 the collar of the wearer. I attain the object by the means set forth in the accompanying drawings.

Figure I shows the tie and fastener in position. Fig. II represents a front view of the 25 fastening device. Fig. III is a cross-sectional view of the device through line z, Fig. II. Fig. IV is an enlarged edge view of the fastener. Fig. V is an enlarged perspective view of the part A. Fig. VI illustrates the operation 30 of clamping the part A.

My fastening consists of the two parts A and B, the part n of B being fastened to the necktie-band either by stitching through a hole o or by means of small clamping projections, as p, punched outward from the plate, 35 as shown in Fig. I. The outer end of this plate n is bifurcated, as shown in Fig. IV, forming a semi-box end h, the two sides being united by a rivet m, and one of the sides h 40 being provided with a tongue f, bent inwardly, as shown. The part A, as shown in Fig. V, is a spring-clasp slotted lengthwise, as at l l, and having points e e inclined toward each other. This spring is placed within 45 the box h h, Fig. IV, the rivet or pin m passing through the slots l l. When the spring is at right angles to the part B, as in Fig. VI, it

will be seen that the casing h h becomes a loop for closing the spring. When nothing is inclosed by the points e e, the spring may 50 be moved within the casing to the limit of the slots l l, when the points e e may be turned about the rivet m as a pivot, as will be made clear by reference to Fig. III; then when the spring is turned to the position shown in Fig. 55 II, the tongue f will fall into the slot l and hold the two parts in that position. The device then becomes a stiffener for passing the band b through the tie. The dotted lines r represent the fabric composing the tie-band. 60

Reference to Fig. I will explain the further use of the fastener. After the tie has been properly adjusted the clasp A is turned to the position shown in Figs. I and VI. The edge 65 of the lower portion of the tie and the edge of a plait in the shirt-bosom are inserted between the points of the spring, and being secured by the loop h the device becomes a fastener to prevent the tie rising about the collar. 70

In the manufacture of this device I do not wish to be confined to the particular shapes herein shown so long as I embody the principles of my invention.

Having described my invention, what I 75 claim, and desire to secure by Letters Patent, is—

1. A necktie-fastener comprising the part B, having a casing h with an extension n for fastening to a band, a rivet m uniting the 80 sides of the casing, and a slotted clasp A, retained within the said casing by means of the rivet m through the said slot, substantially as herein set forth.

2. The combination, in a necktie-fastener, 85 of the casing h, provided with a tongue f, extension n, and rivet m, with the clasp A, provided with slot l, adapted for engagement with the tongue f, substantially as herein set forth.

JOSEPH M. FOX.
